UNITED STATES PATENT OFFICE.

MAX KNORPP, OF NEW YORK, N. Y., ASSIGNOR TO KNORPP CANDY COMPANY, OF BROOKLYN, NEW YORK, A CORPORATION OF NEW YORK.

CANDLE-HOLDER.

1,110,796.

Specification of Letters Patent. Patented Sept. 15, 1914.

Application filed February 17, 1913. Serial No. 748,879.

To all whom it may concern:

Be it known that I, MAX KNORPP, a citizen of the United States of America, residing in New York, in the borough of Brooklyn, county of Kings, and State of New York, have invented certain new and useful Improvements in Candle-Holders, of which the following is a specification.

This invention relates to an improved candle-holder to be used as an ornament for cakes, tarts and other articles of pastry, by which the candle is held in a very effective manner, and which can be furnished at a considerable less expense than the ornamental candle-holders heretofore in use; and for this purpose the invention consists of a candle-holder comprising an exterior ornamental flower of composition-paste or other suitable material and an interior socket formed of a helically-wound wire, which is integral with a pin that passes through the center of the exterior flower-shaped portion for being inserted into the cake or other article.

In the accompanying drawing, Figure 1 represents a side-elevation of my improved candle-holder, Fig. 2 is a vertical central section of the same, and Fig. 3 is a detail side-view of the wire-holder and pin, shown before the composition-body is applied thereto.

Similar letters of reference indicate corresponding parts throughout the different figures of the drawing.

Referring to the drawing, *a* represents the exterior hollow body of my improved candle-holder. The body *a* is made of composition-paste, in imitation of a rose or other flower. In the cavity of the body *a* is arranged a socket *b*, which is made of closely helically-bent wire, that is bent inwardly at its lower end and then in downward direction so as to form a stem or pin *c* for the candle-holder by which the same is inserted into the cake or other article to be ornamented thereby. The connection of the exterior body *a* with the socket *b* is made by forming the composition-paste around the upper end of the stem *c* adjacent to the socket and around the socket *b*, so as to pro-

duce the firm connection of the flower-shaped body *a* with the socket and pin.

By making the stem *c* integral with the socket *b* the strains of use exerted longitudinally on the stem are taken up jointly by the socket and the stem, and thereby the life of the plastic body is prolonged and the security of the connection between the socket, stem and plastic body is preserved. The body *a* strengthens the socket and forms a firm and reliable reinforcement of the same and of the upper part of the stem and of the bent portion of the wire, whereby socket and stem are joined, and thereby renders the device extremely durable.

Any desired ornamental shape may be given to the exterior body, while the one-piece socket and stem may be bent by a special machine, so as to be ready for applying the exterior flower-shaped body thereto. Owing to the small angular spaces formed by the convolutions of the wire socket, the intimate connection of the socket with the flower-shaped body is obtained, in connection with the embedding of the inwardly-extending lower portion *b*¹ and of the stem into the lower portion of the same.

The candle-holder may also be used for Christmas-tree candles, in which case, however, a shorter and pointed stem for applying the candle-holder to the limbs of the tree would be provided. The main purpose of the candle-holder, however, is its use for ornamenting cakes and other articles produced by the skill of the pastry cook.

I claim:

A candle-holder, comprising an exterior ornamental body of plastic material having a socket, a candle-holding socket formed of a closely-wound helically-arranged wire, the convolutions of which laterally contact with each other, and snugly fit the socket of the ornamental body, the top of the wire socket being substantially flush with the top of the ornamental body socket, said wire being bent at the lower end of the socket radially and horizontally inwardly to the central part of the wire socket, and fitting snugly the bottom of the socket of the ornamental body, and then bent to extend out-

wardly away from the wire socket longitudinally thereof in a straight-line extension forming a stem integral with the wire socket, and extending through the bottom of the ornamental body for securing the wire socket and ornamental body together.

In testimony, that I claim the foregoing

as my invention, I have signed my name in presence of two subscribing witnesses.

MAX KNORPP.
